UNITED STATES PATENT OFFICE.

THOMAS I. ASHTON, OF FORT DODGE, IOWA.

HITCHING-POST.

SPECIFICATION forming part of Letters Patent No. 556,798, dated March 24, 1896.

Application filed January 9, 1896. Serial No. 574,924. (No model.)

To all whom it may concern:

Be it known that I, THOMAS I. ASHTON, a citizen of the United States of America, residing at Fort Dodge, in the county of Webster and State of Iowa, have invented a new and useful Hitching-Post, of which the following is a specification.

The objects of this invention are to provide a hitching-post of simple, cheap, strong and durable construction, that when not in use may be concealed in a suitable casing beneath the level of the ground surface or sidewalk, and when it is desired to be used may be quickly and easily elevated and firmly locked in an elevated position where it cannot be accidentally dropped by twisting the post, and, further, to provide a post of this class with a hitching-strap that is automatically drawn into the post when released.

My invention consists in certain details of construction, arrangement and combination of parts, as hereinafter set forth, pointed out in my claim, and illustrated in the accompanying drawings, in which—

Figure 1 shows the complete device with the post in an elevated position and the strap drawn out. Fig. 2 shows a vertical section with the post and strap in the position assumed when not in use. Fig. 3 shows a vertical sectional view in which the post and strap are drawn out. Fig. 4 shows a transverse section on line 4 4 of Fig. 3. Fig. 5 shows a transverse section on line 5 5 of Fig. 3.

Referring to the accompanying drawings, the reference-letter A is used to indicate a casing designed to be placed in the ground and having screw-threads at its top and bottom.

B indicates a cast-metal head screwed into said top and having a lid B² hinged thereto. On the edge of said lid is a curved arm B³ that serves as a handle by which the lid may be raised, and is also so shaped that when the lid is in an open position its end will enter an opening B⁴ in the part B for purposes herein-after explained. Formed in diametrically opposite sides of the lower edge of this part B are two vertical slots C leading upwardly to an annular groove C².

D indicates the post proper, of approximately the same length as the casing A and

having near its lower end the two lugs D² and in its top a slot D³ covered by a metal loop D⁴.

D⁵ indicates an opening in the lower end of the post designed to be entered by the arm B³ when said lugs are in the annular groove 55 and distant from the vertical slots, hence preventing the post from being rotated and thus unlocked inadvertently.

F indicates a hitching-strap passed through the slot D³ and having a weight F² attached 60 to its lower end to move within the post, a snap-hook F³ on its outer end and a swivel-joint F⁴ near its other end. The said loop D⁴ serves to prevent the snap-hook F³ from being drawn into the opening and to prevent 65 the strap from being twisted.

In practical use it is obvious that ordinarily the hitching device will be inconspicuous and yet thoroughly protected from snow, rain, ice, &c. When it is desirable to use the post 70 the lid is elevated by pressure upon the curved arm and the post drawn up and turned part of a revolution until the end of the curved arm drops into the opening in the post by gravity of the lid and thus prevents a further 75 rotation of the post. When, however, it is desirable to lower the post the arm is easily withdrawn by raising the lid. The hitching-strap may then be drawn up and used in the ordinary manner. When released it will 80 automatically be drawn into the post, and a slight turn of the post is all that is necessary to cause it to drop into the sunken pipe.

Having thus described my invention, what I claim as new therein, and desire to secure by 85 Letters Patent of the United States therefor, is—

A hitching-post, comprising a pipe designed to be placed vertically in the ground, and having an opening near the top, an annularly-grooved collar having slots leading downwardly from the groove on the inner top portion of the pipe, a post slidably mounted in the pipe and having an opening near its lower end, designed to align with the aforesaid 90 opening in the pipe when the post is elevated and turned part of a revolution, pins or lugs on the lower end of the post to enter said slots and annular groove, a weight slidably 95 mounted in the post, a hitching-strap at- 100

tached to the weight and extended through the top of the post, and a hinged lid on the pipe having an integral arm designed to automatically enter said openings in the pipe and post when the post is raised and turned and be held therein by the weight of the lid to prevent the post from being turned and

lowered inadvertently, substantially as and for the purposes stated.

THOMAS I. ASHTON.
